METHOD OF DEWAXING OILS

William A. Eberle and Louis H. Zepfier, Jersey
City, N. J., assignors to Standard Oil Develop-
ment Company, a corporation of Delaware

Application June 28, 1933, Serial No. 678,017

4 Claims. (Cl. 62—170)

This invention relates to the dewaxing of oils, especially the lubricating fractions of petroleum, and is more particularly concerned with improvements in the method of chilling.

5 Petrolatum is ordinarily removed from petroleum oils by diluting the oil with a suitable solvent such as naphtha, raising the temperature to a point at which all wax crystals have completely dissolved, chilling the mixture to a wax-separation temperature and then centrifuging the chilled mixture. This may be done by batch operation but is more usually carried out in a continuous manner.

10 In the continuous method of operation the oil-solvent mixture is passed successively through a series of chillers each of which is maintained at a lower temperature than the preceding ones. In order to obtain the petrolatum in particles of a size suitable for rapid centrifuging, it is necessary to chill the oil-solvent mixture very gradually, say at a rate of 2 to 5° F. per hour. Each chiller is maintained at a temperature from 10 to 30° F. below that of the next preceding chiller.

15 It has been found that in passing the partially chilled mixture from one chiller to the next, a sudden drop in temperature frequently occurs at the instant the mixture is introduced into the next succeeding chiller. This shock chilling even though through a narrow temperature range tends to cause the petrolatum to precipitate in particles of relatively small size which do not readily separate out on centrifuging.

20 It is the object of the present invention to provide a method and apparatus for avoiding shock chilling on the passage of the oil-solvent mixture from one chiller to the next.

25 The method will be fully understood from the following description, read with reference to the accompanying drawings, of which

30 Figure 1 is a semi-diagrammatic view in sectional elevation of a single chiller, and

35 Figure 2 is a semi-diagrammatic view of a series of chillers showing the lines of flow through the apparatus.

40 Referring to Figure 1, numeral 1 designates one of the chillers in a series used for continuous chilling. The mixture of oil and solvent is drawn from the next preceding chiller by pump 2 through line 3 and flows through line 4 into and 45 through a coil 5 immersed in the liquid in chiller 1. In this coil 5 the mixture is indirectly cooled by means of the cooler liquid in chiller 1. The partially cooled mixture flows out of coil 5 and if sufficiently cooled is discharged through line 6 directly into the body of liquid in chiller 1. If

5 not sufficiently cooled on one passage through coil 5, the mixture may be recycled therethrough by means of line 7 as many times as is found necessary to bring its temperature to within a few degrees of that of the liquid in chiller 1. Alternatively after one passage of the mixture through the coil approximately one-half of it may be discharged directly into the cooler chiller, and the other half may be mixed with warmer liquid from the preceding chiller and the mixture then 10 passed through the coil. In this way the mixture passing from a warmer chiller to a cooler chiller may be cooled gradually to the temperature of the cooler chiller.

15 Referring to Figure 2 numerals 10, 11, 12, 13, 14 and 15 designate six chillers in series. Numeral 16 designates a supply tank for oil to be dewaxed. Numeral 17 designates a supply tank for diluent to be used. Numeral 18 designates a tank in which the oil and diluent are blended. 20 The mixture of oil and diluent is withdrawn from tank 18 through line 19 by means of pump 20 and forced through a coil 21 immersed in the liquid previously introduced into chiller 10. The mixture may be recirculated through coil 21 as 25 many times as desired, as more clearly indicated in Figure 1. Finally the mixture is discharged through valved line 22 into chiller 10. From chiller 10 the mixture is withdrawn through line 23 by means of pump 24 and recirculated through 30 coil 25 and thence discharged through valved line 26 into chiller 11. In a similar manner, the mixture is passed successively through each chiller.

35 The chilled mixture leaving the last chiller 15 flows into a dewaxing machine 27, wherein the wax is removed and drawn off through line 28. The chilled dewaxed oil is withdrawn through line 29 by pump 30 and forced through line 31 into coil 32 immersed in the liquid in chiller 12. 40 The liquid in chiller 12 is chilled thereby. From coil 32 the chilled oil flows through line 33 into coil 34 in chiller 11 and thence through line 35 into coil 36 in chiller 10. From coil 36 the dewaxed oil flows through line 37 into storage or 45 to apparatus for further treatment (not shown).

50 The last three chillers 13, 14 and 15 are chilled by means of a cooling medium such as brine. The cooling medium is contained in a supply tank 38 from which it is withdrawn through line 39 by pump 40 and forced through line 41 into coil 42 in chiller 15, thence through line 43 into coil 44 in chiller 14, and thence through line 45 into coil 46 in chiller 13. From coil 46 the cooling medium is returned to supply tank 38 through 55

line 47. The quantity of cooling medium supplied to each coil in chillers 13, 14 and 15 may be regulated by means of valved by-pass lines 48, 49 and 50.

5 In the operation of the process it will be understood that any convenient number of chillers may be used and that each chiller may be substantially of the same type as the ones illustrated in the drawings. The solution of oil and solvent 10 may be chilled by any suitable means such as by indirect cooling with brine, the chilled dewaxed oil produced by the process or any other cold medium. The several chillers are maintained at different temperatures by regulating by means 15 of suitable valves the amount of refrigerating medium supplied to the chillers.

It has been found that by this method of operation larger particles of petrolatum are formed and the subsequent separation of the petrolatum 20 from solution in the centrifuges is more efficient, thus allowing greater yields of dewaxed oil to be obtained.

It should be understood that this invention is not limited to the particular method and apparatus described for purposes of illustration but 25 may be adapted to other methods of chilling in which a gradual cooling of the oil-solvent mixture is necessary.

We claim:

30 1. In a process for dewaxing oils in which a mixture of oil and solvent is passed successively through a series of chillers each maintained at a lower temperature than the preceding one, the improvement which comprises passing the oil-

solvent mixture from a preceding chiller through a coil immersed in the liquid in the next succeeding chiller whereby the oil-solvent mixture is indirectly cooled by the cooler liquid and thereafter introducing the oil-solvent mixture directly into 5 the body of liquid in the cooler chiller.

2. In a process for dewaxing oils in which a mixture of oil and solvent is passed successively through a series of chillers the improvement which comprises causing the oil-solvent mixture 10 from a preceding chiller to flow in indirect cold-exchanging relationship with the cooler liquid in the next succeeding chiller, and thereafter introducing the oil-solvent mixture directly into 15 the body of cooler liquid in the said succeeding chiller.

3. Process according to claim 1, in which the oil-solvent mixture from a preceding chiller is recycled through the coil immersed in the liquid of the succeeding chiller until it has been cooled 20 to a temperature within a few degrees of that of the liquid in the said succeeding chiller.

4. Process according to claim 1, in which a portion of the oil-solvent mixture from a preceding chiller which has been passed through the coil 25 immersed in the cooler liquid of the next succeeding chiller is thereafter introduced directly into the body of liquid in the said succeeding chiller, and the remainder of this oil-solvent mixture is recycled through the coil in admixture with an- 30 other portion of oil-solvent mixture from the preceding chiller.
